Primary Examiner — Barbara Fox*Assistant Examiner* — Aram Kwon(74) *Attorney, Agent, or Firm* — Amin, Turocy & Watson, LLP(57) **CLAIM**

The ornamental design for a speaker grill for cars, as shown and described.

DESCRIPTION

FIG. 1 is a front perspective view of a first embodiment of a speaker grill for cars showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right-side elevational view thereof; and

FIG. 7 is a left-side elevational view thereof.

FIG. 8 is a front perspective view of a second embodiment of a speaker grill for cars showing our new design;

FIG. 9 is a front elevational view thereof;

FIG. 10 is a rear elevational view thereof;

FIG. 11 is a top plan view thereof;

FIG. 12 is a bottom plan view thereof;

FIG. 13 is a right-side elevational view thereof; and,

FIG. 14 is a left-side elevational view thereof.

The broken lines shown in the figures depict portions of the speaker grill for cars that form no part of the claimed design.
